[57] CLAIM

The ornamental design for a portable laptop computer, as shown and described.

DESCRIPTION

FIG. 1 is a perspective view of the top, front and right side with an outer cover in the open position of a portable laptop computer showing our new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a left side elevational view thereof;
FIG. 7 is a right side elevational view thereof;
FIG. 8 is a right side elevational view thereof with an inner cover in the raised position;
FIG. 9 is a perspective view similar to FIG. 1 with the outer cover and inner cover in the raised position; and,
FIG. 10 is a perspective view similar to FIG. 1 with the inner and outer covers in the closed position thereof.
